(57) **CLAIM**

The ornamental design for a shotgun shell feeder as shown and described.

DESCRIPTION

FIG. 1 is a front perspective view of a shotgun shell feeder showing my new design;

FIG. 2 is a left-side elevation view thereof;

FIG. 3 is a right-side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is another front perspective view thereof with the front panel removed.

The broken lines depict portions of the shotgun shell feeder that form no part of the claimed design.
